HYDRAULIC RAM SYSTEM HAVING CONDITIONING MEANS TO RESIST CORROSION

John A. Kile, St. Cloud, Minn., assignor to Nationwide Sales Corporation, St. Cloud, Minn., a corporation of Minnesota

Application August 25, 1954, Serial No. 452,149

5 Claims. (Cl. 60—51)

This invention relates to a hydraulic ram system and 15 more particularly to a hydraulic hoist or jack which is subject to operation in a corrosive atmosphere.

Equipment and tools which are operated or stored in a corrosive atmosphere such as exists in radiator shops, lead 20 burning establishments, soldering shops and numerous other technical manufacturing and repairing buildings, are subject to rapid deterioration and may be completely ruined in a matter of several weeks or months unless proper precautions are taken to prevent the surface of such equipment and tools from becoming contaminated by the atmosphere. Radiator repair shops, in particular, have an atmosphere containing hydrochloric acid fumes because of the large quantity of hydrochloric or muriatic acid which is used in preparing surfaces to be soldered in the manufacture and repair of radiators. The tools and 25 other equipment in such shops deteriorate rapidly. In the case of small tools such as pliers, screw drivers and the like, they may be replaced at low cost, but where electric motors, hydraulic equipment and the like are ruined in a short time, the large investment makes the 30 corrosion a problem of great concern to the operators of the shops. This invention is particularly concerned with hydraulic jacks and hoists and it has been noted that where such equipment is employed in a radiator shop, they are not corroded when covered with oil at all times, but in those areas where oil is not constantly supplied, the acid 35 fumes rapidly pit and corrode the equipment. It has been observed that piston cylinders which are subject to acid atmosphere quickly develop rough and dry surfaces and, where resilient piston members are employed, they also become rapidly worn and inoperative. Furthermore, after the corrosion sets in, the operation of the 40 device is no longer smooth but becomes jerky and not dependable. Even where such hydraulic equipment is used every day, the acid atmosphere within the cylinder attacks the dry surfaces during the night and soon will ruin the equipment.

It is therefore an important object of the present invention to provide a simple and inexpensive hydraulic ram system where the parts normally subject to corrosion are easily and quickly conditioned to constantly resist attack.

Another object of the invention is to provide a hydraulic hoist in which means are provided for displacing acid atmosphere from within the device and simultaneously for replacing the corrosive air with clean air bearing atomized oil particles which coat the walls of the cylinders.

It is a further object to provide a hydraulic hoist in which the cylinder operates with a head of oil constantly supplied over the piston as well as underneath, the excess head of oil being returned to an oil reserve.

A still further object is to provide apparatus of the class described in which excess cylinder oil is safely accumulated during each day, and when the apparatus is shut down at night a portion of the excess oil is atomized and coated on the inside of the hydraulic cylinder, the remainder of the excess oil being permitted to flow back to a reservoir.

2

These and other objects and advantages of the invention will more fully appear from the following description made in connection with the accompanying drawing, wherein like reference characters refer to the same or similar parts throughout the several views, and in which:

Fig. 1 is a side elevation of my hydraulic ram system, portions thereof being shown in vertical section; and

Fig. 2 is an enlarged vertical section of that segment of the device which includes the bottom of the cylinder and the piston assembly.

Referring now more particularly to the drawing, my invention includes a hydraulic ram of somewhat conventional structure but having certain limitations for specific purposes as will be disclosed as this specification progresses. The hydraulic ram has an upstanding cylinder indicated generally at 10 and preferably constitutes a lower straight portion 11 communicating with a somewhat enlarged upper cylindrical portion 12, the entire cylinder being mounted in fluid-tight relation upon a base member 13 and having a gland member 14 threadably mounted on the upper end of the cylinder and provided with a medial opening 15 through which a plunger or piston rod 16 can vertically slide. I prefer to maintain a slight clearance between the walls of opening 15 and the outer surface of piston rod 16 so as to permit the escape and entrance of air therebetween in a free but partially restricted manner. The piston rod 16 preferably comprises a tubular member of constant diameter which extends for the full length of the cylinder or barrel 10 and has disposed at its lower end a piston assembly 17.

The piston assembly is shown in detail in Fig. 2 and comprises a sealing ring 18 having a central opening 19 through which the reduced shoulder 20 of a fastening member 21 may extend. At the underside of the sealing ring 18 is a washer member 22 and another bearing member 23. A compression spring 24 is adapted to surround the reduced portion 20 of the securing member 21 and another washer 25 bears against the underside of the compression spring 24. A cotter key 26 is adapted to interfit with a transverse opening 27 so as to maintain the entire piston assembly under compression.

Means such as central opening 28 is provided for permitting seepage of fluid through the piston assembly from below the piston to the upper side thereof to maintain the entire piston assembly 17 in a bath of lubricating fluid such as oil. A bolt 29 containing a weep hole 30 may be threadably secured in the upper orifice of opening 28 to control the rate of seepage through the piston assembly.

Also mounted on base 13 is a fluid reservoir which is an enclosed member adapted to hold a quantity of lubricating and corrosion-resistant fluid 32 as shown in Fig. 1. The reservoir 31 has fluid communication at 33 with the lower end of hydraulic cylinder 10 and at a position beneath the piston 17. The enclosed reservoir 31 communicates with a source of air pressure 34 through a valve mechanism 35 which is preferably of the three-way type, permitting compressed air to be introduced through orifice 36 so as to place fluid 32 under compression, or may be adjusted so that compressed air may be permitted to escape through the opening 37. The reservoir 31 may be physically carried as by bracket 38 to the side of hydraulic cylinder ram 10 for rigid support. A by-pass collector 39 is disposed in interconnecting relation with an upper portion of the cylinder 10 and the reservoir 31. This is best effected by an overflow pipe 40 which is connected with a lower part of the upper enlarged cylinder portion 12 and also an upper portion of the by-pass collector 39. The lower portion of the by-pass collector and preferably at the bottom 41 has fluid connection through tube 42 with the upper space 43 in the reservoir 31. A valve 44 is adapted to open or close the tubular connection 42 as desired to

place my invention in operation. The tube 42 extends upwardly within the enclosed by-pass collector 39 and terminates in an open mouth 45 in spaced relation with the top 46 of the collector. One or more openings 47 are disposed through the tube 42 and above the bottom 41 of collector 39 so that by-passed fluid 48 can flow downwardly therethrough and into the reservoir 31 when valve 44 is in open position.

A fluid gauge 49 of ordinary construction is placed externally of the by-pass collector 39 and has fluid communication with the upper portion of the collector at 50 and with the lower portion at 51. The glass tube 52 shows at all times the level of fluid 48 within the collector.

The collector 39 and reservoir 31 provide as a unit, a by-pass system for returning fluid 53 which has accumulated above the piston assembly 17.

In the use and operation of my hydraulic ram system in corrosive atmospheres such as the acid-laden air of a radiator shop, I utilize the ram system for hoisting radiators and other heavy equipment through the upwardly extending plunger or piston rod 16 and actuate the assembly through the introduction of compressed air in tube 34 and controlled by valve 35. When air is permitted to enter under compression to the upper space 43 in reservoir 31, the fluid 32, which is preferably a lubricating oil having corrosion-inhibiting property, is caused to flow through the interconnection 33 and force piston assembly 17 outwardly together with the piston rod 16. The small bleed hole 30 in the bolt 29 permits a constant seepage of the pressurized fluid to collect above the piston assembly and surrounds the lower end of piston rod 16 as shown in Fig. 1. Since the piston rod has openings 54 to permit communication between the seep or bleed passageway 30 and the annular space between piston 16 and cylinder walls 11, the fluid head 53 will continuously lie thereover and maintain the piston assembly in a bath of oil. This bath of oil is especially useful in preventing the sealing ring 18 from sticking and rubbing on the inside of cylinder 11. If the head 53 rises excessively, it will overflow through the connection 40 into by-pass collector 39 whenever the piston rod 16 is extended to an upper position and the collected fluid 48 will continue to accumulate during the day's operation with the level thereof being observable in the glass tube 52 of gauge 49. The bleed hole 30 is selected so as to permit a quantity of fluid not in excess of volume of the by-pass collector 39 to accumulate in a period of operation suitable to the circumstances. This period is usually one day's operation with the machine being shut down during the night.

When it is desired to discontinue operation of the hydraulic system and its driven equipment, the piston is raised to its upper limit through pressure of air from tube 34 so as to by-pass most of the head of overlying fluid 53. The valve 35 is then shut off and valve 44 is opened. The back pressure of the space 43 within reservoir 31 will cause air to surge upwardly through tube 42 and blow out the upper end of the pipe so as to remove the level of lubricating fluid collected therewithin. As air continues to rush upwardly through the tube 42, collected oil 48 will flow into the small openings 47 and be atomized along with the air blowing through the tube. The air continues into the upper space within the enlarged portion 12 and downwardly into the narrower portion 11 as the piston assembly sinks downwardly. All corrosive air which has accumulated within the cylinder during the day's operation is thus swept out through the clearance between the gland 14 and piston rod 16 and at the same time the atomized oily fluid deposits a film of the oil over all of the internal parts which were previously exposed to the acid atmosphere. The system is then allowed to come to rest, com-

pletely protected from corrosion and ready for operation on the following day.

It may thus be observed that I have devised a hydraulic ram system which will preserve the utility of the ram over extended periods of time, even in the presence of strongly corrosive atmosphere, the parts being easily and quickly maintained out of contact with corrosive air by simple and novel by-pass means. At the same time, the system also provides a continuous bath of lubricating fluid above and below the piston so as to insure smooth and easy operation.

It will, of course, be understood that various changes may be made in the form, details, arrangement and proportions of the various parts without departing from the scope of my invention.

What is claimed is:

1. In a hydraulic ram system adapted to be operated in a corrosive atmosphere, said ram having a cylinder, a piston, a fluid reservoir and a fluid pressure communication from the reservoir through an enclosed end of the cylinder at one side of the piston for actuating the ram, the combination of bleed means supplying continuously at least a small head of fluid through the cylinder to the other side of the piston to maintain the piston in a bath of fluid, a valved by-pass interconnecting the space in the cylinder at said other side of the piston and the reservoir for returning excess head of fluid to the reservoir, and an air pressure connection with the valved by-pass for supplying air reversely through the by-pass for sweeping out corrosive gas in said space in the cylinder with atomized fluid, said atomized fluid being supplied from a portion of the by-passed excess head of fluid.
2. In a hydraulic ram system adapted to be operated in a corrosive atmosphere, said ram having a cylinder, a piston, a fluid reservoir and a fluid pressure communication from the reservoir through an enclosed end of the cylinder at one side of the piston for actuating the ram, the combination of means for supplying at least a small head of fluid through the cylinder to the other side of the piston to maintain the piston in a lubricating and corrosion-inhibiting bath of fluid, a valved by-pass interconnecting the space in the cylinder at said other side of the piston and the reservoir, and an atomizing tube located in said by-pass and adapted to permit excess head of fluid to be returned downwardly therethrough to the reservoir and to permit upward flow of pressurized air for sweeping out corrosive atmosphere from the space in the cylinder and replacing the corrosive atmosphere with non-corrosive air having atomized particles therein.

3. A hydraulic ram system for resisting attack by corrosive atmosphere comprising, an upstanding hydraulic cylinder, a piston rod disposed within the cylinder and having an extension for applying force and movement externally of the cylinder, a piston secured to the piston rod and slidable vertically within said cylinder, a reservoir adapted to contain lubricating and corrosion-inhibiting fluid and having connection for supplying the fluid therefrom under pressure to said hydraulic cylinder beneath the lowermost stop position of said piston, means supplying said fluid to space in said cylinder above the piston to maintain continuously thereover a head of fluid, an enclosed by-pass collector having overflow fluid communication with an upper part of the cylinder for collecting excess fluid from above the piston during operation of the ram system, and a valved interconnection disposed in fluid communication with the by-pass collector and with the reservoir, said valved interconnection in open position permitting first exhaust air from the reservoir to atomize a portion of said fluid and sweep out corrosive air from within the cylinder while depositing a film of fluid on the inner walls of the cylinder then permitting the collected fluid in the collector to drain back into the reservoir.
4. The combination, with an upstanding hydraulic cylinder, a piston member slidably disposed within the

cylinder, and a reservoir of hydraulic fluid adapted to be supplied under pressure to the cylinder below the piston, of seepage means communicating between the reservoir and the space above said piston for permitting the slow accumulation of a head of fluid over the top thereof, a by-pass collector communicating between the reservoir and an upper position of said cylinder for returning excess fluid from above the piston to the reservoir during operation of the piston member, and tubular means communicating with said by-pass collector and having a nozzle portion disposed vertically therewithin for permitting excess fluid to flow therethrough to the reservoir and permitting pressurized air to flow upwardly therethrough while atomizing a portion of said excess fluid for sweeping out corrosive air from within the entire cylinder.

5. In a hydraulic ram system adapted to be operated in a corrosive atmosphere, said ram having a cylinder, a piston, a fluid reservoir and a fluid pressure communica-

tion from the reservoir through an enclosed end of the cylinder at one side of the piston for actuating the ram, the combination of bleed means supplying continuously at least a small head of fluid through the cylinder to the other side of the piston to maintain the piston in a bath of fluid, a collector for overflow of said small head of fluid communicating with the cylinder at said other side of the piston, and air pressure means adapted to atomize at least a portion of the overflow fluid and communicating with said other side of the piston in said cylinder to reversely sweep out corrosive atmosphere therefrom and to coat exposed parts with atomized fluid.
